Attn:

UNITED STATES PATENT OFFICE.

WILLIAM LUTH, OF ALBION, NEBRASKA.

LIGHT-SHIELD.

1,273,637.

Specification of Letters Patent. Patented July 23, 1918.

Application filed January 8, 1917. Serial No. 141,238.

To all whom it may concern:

Be it known that I, WILLIAM LUTH, a citizen of the United States, residing at Albion, in the county of Boone and State of Nebraska, have invented certain useful Improvements in Light-Shields, of which the following is a specification, reference being had therein to the accompanying drawing.

The present invention relates generally to improvements in light shields and more particularly has reference to a shield especially adapted for use in connection with electric light bulbs.

It is the primary aim and object of the present invention to provide novel means on a light shield with which an electric lamp bulb and its socket will coöperate whereby to maintain the shield in adjusted positions with respect thereto, thus reflecting the light rays in various directions, the device incidentally being of such a character that it may be readily adapted by motorists for dimming the headlights on a motor vehicle.

As a more specific object, the present invention contemplates the provision of a novel bearing surface on the attaching means and the body of the shield for increasing the efficiency of the engagement of a lamp bulb with the shield.

Among the other aims and objects of the present invention may be recited the provision of a device of the character mentioned with a view to compactness, and in which the number of parts are few, the construction simple, the cost of production low and the efficiency high.

Other objects as well as the nature, characteristic features and scope of my invention will be more readily apparent from the following description taken in conjunction with the accompanying drawings and pointed out in the claim, forming a part of this specification.

The preferred embodiment of the present invention is clearly illustrated in the accompanying drawings, in which:—

Figure 1 is a side elevation of my invention in operative relation with a lamp bulb and its socket, parts being shown in sections.

Fig. 2 is a top plan of Fig. 1 partly taken in longitudinal section on line 2—2 of Fig. 1, in the direction which the arrows point, and

Fig. 3 is a transverse section of the shield taken on line 3—3 of Fig. 1 in the direction in which the arrows point.

Similar characters of reference are employed in all of the above described views, to indicate corresponding parts.

Referring now, more particularly, to the accompanying drawings, I have illustrated a lamp socket 1, of the conventional form and removably mounted therein is a stem 2 of a lamp bulb 3, which may be and preferably is of a globular form. Secured in an adjusted position and partly surrounding the bulb is my improved reflecting shield designated in its entirety by the numeral 4.

In the present instance the shield consists of a body 5, preferably of a semi-globular configuration the outer end having a recess 6 therein for surrounding the usual pointed end of the bulb. An extension 7 is integral with and continues from the inner edge of the body in a plane at right angles to the plane of the straight edges 8 of the body while an opening 9 is provided in the extension and the body as indicated in Fig. 3. The side edges of the extension adjacent the body are curved as indicated by the numeral 10 and the side portions 11 adjacent the body and between the opening and the curved edges 10, are also curved to correspond to the curvature of the body, the curvature of these portions 11 causing the curved edges 10 to be arranged toward the inner end of the bulb in order that the said curved edges 10 may form a bearing surface for the bulb subsequent to the projecting of the stem 2 through the opening 9. Incidentally, this opening permits of the bulb holding the extension against the socket 1, since the extreme inner end of the bulb engages the extension while the curved edges 10 are also engaged by portions of the bulb adjacent the inner end. The inner surface of the body may be coated with a silvered coating to provide a reflecting surface.

From the foregoing description it will be readily apparent that the body 5 may be adjusted about the bulb preparatory to the final turning of the bulb to clamp the body. It is also thought that the advantages of the invention when in use will be readily apparent. For instance, the shield may be readily applied on a bulb in a headlight for dimming the headlight.

It will be understood that the above description and accompanying drawings comprehend only the general and preferred em-

bodiment of my invention and that various minor changes in detail of construction, proportion and arrangement of the parts may be made within the scope of the appended claim and without sacrificing any of the advantages of my invention.

Having thus fully described my invention, what I claim as new and desire to secure by Letters Patent, is:—

- 10 In a device as described, in combination, an electric light bulb having a pointed teat, a threaded shank connected thereto, a sleeve in which said shank is threaded, a shield consisting substantially of a semi-spherical

metallic member adapted to overlie one half 15 of said bulb, a lug formed upon said shield and forming a flat projection therefrom, said lug provided with an opening through which said shank projects, said sleeve bearing frictionally against said flat lug, the 20 forward portion of said shield terminating in a tapering portion the extremity of which is curved back to form a protecting lip spaced in back of the mentioned teat of said bulb.

25 In testimony whereof I affix my signature.

WILLIAM LUTH.
